Primary Examiner — Ian Simmons

Assistant Examiner — Rhea Shields

(57) **CLAIM**

I claim the ornamental design for an electrical junction box gasket, as shown and described.

DESCRIPTION

FIG. 1 is a perspective view taken from the bottom and one side of the design;

FIG. 2 is a front elevational view of the design shown in FIG. 1;

FIG. 3 is a right side elevational view of the design shown in FIG. 1;

FIG. 4 is a rear elevational view of the design shown in FIG. 1;

FIG. 5 is a left side elevational view of the design shown in FIG. 1;

FIG. 6 is a top elevational view of the design shown in FIG. 1; and,

FIG. 7 is a bottom elevational view of the design shown in FIG. 1.

The broken line portions in the drawings are for illustrative purposes and do not form part of the claimed design.

1 Claim, 4 Drawing Sheets
